UNITED STATES PATENT OFFICE.

HARRY P. KOSTER, OF LOS ANGELES, CALIFORNIA.

DESIGN FOR A SHAFT-IRON FOR BUGGY-SHAFTS.

SPECIFICATION forming part of Design No. 34,681, dated June 4, 1901.

Application filed October 24, 1900. Serial No. 34,222. Term of patent 7 years.

To all whom it may concern:

Be it known that I, HARRY P. KOSTER, a citizen of the United States, residing at Los Angeles, in the county of Los Angeles and State of California, have invented and produced a new and original Design for Shaft-Irons for Buggy-Shafts, of which the following is a specification, reference being had to the accompanying drawing, forming a part hereof, which is a perspective view of shaft-irons in which is embodied my reinforcing heel-plate, looking at the bottom thereof, so as to clearly show the configuration of the same.

As shown in the drawing, the leading or material feature of my design consists in the configuration of the reinforcing heel-plate B, which extends forward and back of the point of junction therewith of the brace-rod A,

the brace-rod being integral with the heel-plate, thereby giving to the shafts when secured thereto greater strength at this point, where the ordinary shaft is usually weak and liable to break, and also giving the shafts a neat and light appearance.

Having described my invention, what I claim as new, and desire to secure by Letters Patent, is—

The design for a shaft-iron for buggy-shafts as herein shown and described.

In witness that I claim the foregoing I have hereunto subscribed my name this 1st day of October, 1900.

HARRY P. KOSTER.
